(57) **CLAIM**

I claim the ornamental design for the pocket knife, as shown and described.

DESCRIPTION

FIG. 1 is a front, left, and top perspective view of a pocket knife in accordance with the present invention, wherein the pocket knife is in a closed state, such that a blade of the pocket knife is in a pocket of the pocket knife;

FIG. 2 is a front elevational view of the pocket knife of FIG. 1 in the closed state of FIG. 1;

FIG. 3 is a rear elevational view of the pocket knife of FIG. 1 in the closed state of FIG. 1;

FIG. 4 is a left side elevational view of the pocket knife of FIG. 1 in the closed state of FIG. 1;

FIG. 5 is a right side elevational view of the pocket knife knob of FIG. 1 in the closed state of FIG. 1;

FIG. 6 is a top plan view of the pocket knife of FIG. 1, in the closed state of FIG. 1;

FIG. 7 is a bottom plan view of the pocket knife of FIG. 1, in the closed state of FIG. 1;

FIG. 8 is a front, left, and top perspective view of the pocket knife of FIG. 1, wherein the pocket knife is in an open state, such that a blade of the pocket knife outside of the pocket of the pocket knife;

FIG. 9 is a front elevational view of the pocket knife of FIG. 1 in the open state of FIG. 8;

FIG. 10 is a rear elevational view of the pocket knife of FIG. 1 in the open state of FIG. 8;

FIG. 11 is a left side elevational view of the pocket knife of FIG. 1 in the open state of FIG. 8;

FIG. 12 is a right side elevational view of the pocket knife knob of FIG. 1 in the open state of FIG. 8;

FIG. 13 is a top plan view of the pocket knife of FIG. 1, in the open state of FIG. 8; and,

FIG. 14 is a bottom plan view of the pocket knife of FIG. 1, in the open state of FIG. 8.
